JOINT FOR COSTUMERS AND OTHER ARTICLES

Filed Oct. 10, 1928

UNITED STATES PATENT OFFICE

HARRY SUMNER BEST, OF GALVA, ILLINOIS, ASSIGNOR TO JOHN H. BEST & SONS, OF GALVA, ILLINOIS, A FIRM COMPOSED OF CHARLOTTE SUMNER BEST, DON JEWELL BEST, LEON HENSON BEST, AND HARRY SUMNER BEST

JOINT FOR COSTUMERS AND OTHER ARTICLES

Application filed October 10, 1928. Serial No. 311,476.

This invention relates to joints for costumers, sewing cabinets, tables, and other articles.

The object of the invention is to provide a novel joint of strong and substantial construction adapted to hold several parts rigidly together in permanent fixed relation.

Further objects of the invention are to provide a joint which comprises few parts, which is simple in construction, which interlocks the parts to provide rigidity, and which can be easily tightened if required, to take up looseness due to the wood drying or for other reasons.

The primary object of the invention is to provide a strong, substantial and rigid joint for the column and the cross pieces providing the feet for a costumer, and the invention can be embodied in stretchers for different articles of furniture, for furniture legs, and pedestals, and for other things wherein a joint of this kind is desirable and useful.

In the accompanying drawings I have illustrated the invention in a costumer, and referring thereto—

Fig. 1 is a perspective view of a costumer embodying the invention;

Fig. 2 is an exploded view illustrating the relative position of the parts which constitute the joint;

Fig. 3 is a detail bottom plan view;

Fig. 4 is an exploded view of another form of the joint;

Fig. 5 is a detail bottom plan view of the joint shown in Fig. 4;

Figs. 6 and 7 are detail views of the leg members of the joint shown in Figs 4 and 5.

Referring to the drawings, the costumer comprises a column 8 mounted on two feet members 9—10 which are crossed at the middle and joined together and with the column. The sides of the feet member 9 are mortised at 11, and the bridge portion 12 is halved as indicated at 13. The sides of the feet member 10 are mortised at 14, and the bridge portion 15 is halved as indicated at 16. The construction is such that the bridge 15 is adapted to fit in the socket 17 formed by halving the bridge 12, and the bridge 12 is adapted to fit in the socket 18 formed by halving the bridge 15. When the feet members are thus inter-

locked, they will be held in proper relation at right angles to each other, and a screw opening 19 is provided through the interlocking bridges. Four square openings 20 are formed at diagonal opposite corners of the interlock of the feet members, and they are adapted to receive four square tenons 21 formed on the lower end of the column 8. When the feet members are interlocked and the tenons of the column are engaged with the openings 20, a lag screw 22 is inserted in the central opening 19 and engaged with the column to secure the feet members to the column.

In Figs. 4-7 I have shown a different embodiment of the invention, wherein the feet member 23 is mortised at the bottom at 24 and the feet member 25 is mortised at the top at 26 so that the two feet members will interlock like the feet members 9 and 10. The feet member 23 is also mortised at 27 and the feet member 25 is mortised at 28, at the four corners of the interlock of the feet members. The bridge 29 of the feet member 23 and the bridge 30 of the feet member 25 are provided with openings 31 to receive the lag screw 32 for securing the feet members to the column 8. This column is made with tenons 21 to engage the openings formed by the mortises 27, 28 when the feet members 23, 25 are interlocked as shown in Fig. 5, as previously described in connection with Figs. 1 and 2.

In the construction of Figs. 1 and 2 the bridges are formed by mortising the feet members at the sides and then halving the bridges, whereas in the construction of Figs. 4-7 the bridge members are formed by mortising the feet members at the top and bottom respectively, after which the members are mortised at the sides for forming the openings to receive the tenons. More operations are required in producing the joint of Figs. 4-7, and for economical reasons the joint of Figs. 1, 2 is preferred, although both joints are strong and substantial and the interlocked feet members provide the openings for receiving the corner tenons of the column. When the feet members are interlocked, they will be held in rigid right-angular relation; and when the four tenons of the column are engaged with the openings in the

interlocked feet members, the latter will be rigidly secured in their interlocked position. Thus, the interlocking structure of the feet members provides for a rigid connection, and the four tenons fitting in the four square openings disposed about the interlocking connection constitute an effective clamping means for preventing any relative movement of the feet members. In the construction of Fig. 2 each opening for a tenon 21 is formed between the bridge 11, the bridge 12 and the shoulders 11' formed by the mortises 11 and the shoulders 14' formed by the mortises 14. In the construction of Figs. 4-7 each opening for a tenon 21 is formed between a shoulder 26' on the member 25 and a shoulder 27' on the member 23 and the walls of the mortises 27 and 28. In both constructions the tenons form locks at each corner of the interlock of the feet members to coact with said interlock for holding the feet members in rigid engagement and at the same time holding the column in rigid engagement with the interlocked feet members.

So long as the three parts, the column and the two feet members, are interlocked, they will be held rigidly in their proper relation, and the lag screw is provided to insure that the members will remain in their interlocked position. The joint is simple in construction in either form, it is easily made and assembled, and it prevents movement of any of the parts relative to the other parts in any direction. The invention is particularly desirable for a costumer, but it can also be used in stretchers for different articles of furniture, for gate-leg tables, and in many other articles where a rigid joint of this kind is desirable.

I have shown the invention in forms which I have found satisfactory for the purpose, but I reserve the right to make all such changes in the form, size, construction and arrangement of parts within the scope of the following claims.

I claim:

1. A joint comprising a pair of crossed interlocked feet members and a column having a plurality of corner disposed tenons, said feet members being mortised to provide bridges and said bridges being halved to interlock, said members being of substantially the same width and the length of said bridges being substantially equal to the width of said members whereby rectangular enclosed openings are formed diagonally disposed with respect to the center of the interlocked members to receive the tenons of said column.

2. A joint comprising a pair of crossed and interlocked feet members and a column having a plurality of corner disposed tenons, said feet members being mortised to provide bridges and said bridges being halved to interlock, the width of the members being substantially the same and the length of each mortise being substantially equal to the width

of its member whereby rectangular enclosed openings are formed diagonally disposed with respect to the center of the interlocked members to receive the tenons of said column.

3. A joint comprising a pair of crossed and interlocked feet members and a column having a plurality of corner disposed tenons, said feet members being mortised to provide bridges and said bridges being halved to interlock, the width of the members being approximately the same and the length of each bridge and the length of each mortise being substantially equal to the width of its member whereby rectangular enclosed openings are formed diagonally disposed with respect to the center of the interlocked members to receive the tenons of said column.

HARRY SUMNER BEST.
